[57] CLAIM

The ornamental design for a "base for a rifle telescope mount", as shown and described.

DESCRIPTION

FIG. 1 is a perspective view of the "Base for a Rifle Telescope Mount", showing my new design;

FIG. 2 is a top view thereof;

FIG. 3 is a side elevational view (which shows the "outer" side of the base);

FIG. 4 is a bottom view thereof;

FIG. 5 is a side elevational view (which shows the side that lies immediately next to the rifle);

FIG. 6 is a front elevational view thereof; and

FIG. 7 is a rear elevational view thereof.

FIG. 1
